UNITED STATES PATENT OFFICE

ANNIE L. HERTZBERG, OF OAKLAND, CALIFORNIA

SHIRT

Application filed February 27, 1932. Serial No. 595,492.

This invention is an improvement in shirts having detachable collars and is particularly directed to the low cut V neck type which is especially suitable for wear in hot climates.

5 The main object of the invention is to provide a garment of the character indicated which will be neat in appearance, cool and comfortable.

Another object of the invention is to provide 10 a shirt collar and neck band of low cut V type which will not have the inherent tendency of separating, the usual detachable collar having a tendency to creep over the neck band.

15 Other objects and advantages of the invention will become apparent as the following description is read on the drawing forming a part of this specification and in which similar reference characters are used to designate 20 similar parts throughout the several views of which:

Fig. 1 is a pattern view of the collar showing the anti-creep means and the specific form 25 which causes the collar points to lie flat on the chest of the wearer while the collar back lies flat on the back of the neck.

Fig. 2 is a front perspective view of the collar attached to the shirt and showing the upstanding back and chest conforming collar 30 points.

Fig. 3 is a side view of Fig. 2.

Fig. 4 is a view similar to Fig. 2 with the collar removed.

The collar 10 is cut to such form that when 35 worn with a shirt 11 having a V cut neck, cut very low on the chest of the wearer and edged with a neck band which is very high at the back with the buttonhole 14 placed close to the top edge, the neck band tapering curvilinearly from the back to the front ends 15 which lie flat on the chest of the wearer and stitched flat to, and on the bias with the front button panel, will cause the back of the collar 40 to extend above the coat collar, prevent the sides of the collar from creeping up over the neck band and cause the points 16 to lie flat on the chest, gradually conforming to the back and sides of the neck of the wearer, the collar gradually curving both ways at about 45 the indicated dotted line 17.

To obtain this conformation the special neck band Fig. 4 is required in conjunction with the special form of collar shown in Fig. 1, in which the collar portion proper is substantially straight between points 18 and 19, 55 thence curving outwardly and continuing into a reverse compound curve forming the points 20 and 21, the collar portion proper increasing in width from the center at the back to the points, the lower edge 22 being 60 concavously formed, the collar band being complementarily formed at its upper edge.

The collar band is similarly formed to the neck band, being very high at the back, but has the buttonhole 23 located near the 65 lower edge instead of near the upper edge as in the neck band. The collar band lower edge is concavously formed at the back as indicated at 24, continuing into reverse curves in both directions, being very wide at 25 and 70 26, which portions continue into reverse curves at 27 and 28 and terminate in comparatively narrow button tabs 29 and 30 which are provided with buttonholes 31 and 32, the points of the collar being retracted 75 from the ends of the tabs as indicated at 33.

When worn, the back of the collar extends comfortably above the coat collar 34 as shown in Fig. 3, while the front end and points lie flat on the chest, as also do the button tabs of 80 both, the collar band and neck band.

The collar is obviously cool and comfortable and not adapted to creep over the neck band, a fault common with the usual detachable collar, the specific form of both, collar and neck band obviating any tendency of such nature. The point at which a collar customarily creeps is in the vicinity of 13-16 85 in Fig. 3, at which point the collar band and neck band are unusually wide, and corresponds to the areas 25 and 26 Fig. 1.

I claim:

1. In combination with a shirt having a low cut V neck, and provided with a neck band comparatively high at the back with a 95 buttonhole located adjacent the upper edge; a collar comprising a collar portion and a neck band portion, said neck band portion being comparatively high at the center with a buttonhole located adjacent the bottom and 100

continuing by compound curves into broad portions to prevent creep and continuing into comparatively narrow tabs extending beyond the collar portion.

- 5 2. In combination with a low cut V neck shirt, a neck band on said shirt comparatively high at the center and having a buttonhole adjacent the upper edge, continuing into narrow buttonhole tabs with intermediate
- 10 10 wide, anti-creep portions, a collar comprising a collar portion and a neck band portion seamed together, said neck band portion being of similar form to the neck band of said shirt except having the rear buttonhole located adjacent the lower edge.
- 15 3. In combination with a shirt having a low cut V neck, a collar comprising a collar portion and a neck band portion seamed together, said collar portion being concavously
- 20 20 formed at the seam, said neck band portion being complementarily formed at the seam, the neck band portion being comparatively wide at the center and having a greater width portion on both sides of the center and
- 25 25 continuing curvilinearly into comparatively narrow tab portions, said tab portions continuing beyond the ends of the collar portion, and a neck band of similar form, for said low cut V neck, said greater width portions forming
- 30 30 projecting anti-creep portions at the points which are normally most subject to creep, and the specific form of the neck band portions causing the points of the collar portion and the tabs to lie flat on the chest of the
- 35 35 wearer.

In testimony whereof I affix my signature.
ANNIE L. HERTZBERG.
